CLAIM

I claim the ornamental design for an electronic display case with releasable, laminated tear-off film.

DESCRIPTION

FIG. 1 is a front perspective view of my electronic display case with releasable, laminated tear-off film;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a bottom view thereof, the dot pattern representing a textured surface; and,

FIG. 8 is a perspective view thereof shown in an open position and in a, environment of use, the broken lines forming no part of the claim.
